US00D568155S

(12) United States Design Patent (10) Patent No.: US D568,155 S
Glydon et al. (45) Date of Patent: * May 6, 2008

(54) PINCHED HOUR GLASS CONTAINER

(75) Inventors: James A. Glydon, Hackettstown, NJ (US); Simon Gainey, Media, PA (US); Tom Wells, Chadds Ford, PA (US); Rita Dombroski, Claymont, DE (US)

(73) Assignee: Cadbury Adams USA LLC, Parsippany, NJ (US)

() Term: 14 Years

(21) Appl. No.: 29/267,977

(22) Filed: Oct. 26, 2006

(51) LOC (8) Cl. 09-01

(52) U.S. Cl. D9/500

(58) Field of Classification Search D9/424, D9/428, 446-447, 449, 454, 500, 502-505, D9/516, 549, 550, 557-558, 682, 686, 688-691, D9/694, 905; D7/598; 215/379-384; 220/660, 220/662, 669-673, 675

See application file for complete search history.

(57) CLAIM

The ornamental design for a pinched hour glass container, as shown and described.

DESCRIPTION

FIG. 1 is a top, front, right side perspective view of a pinched hour glass container with lid showing our new design;

FIG. 2 is a front elevation view thereof;

FIG. 3 is a right side elevation view thereof;

FIG. 4 is a rear elevation view thereof;

FIG. 5 is a top plan view thereof; and,

FIG. 6 is a top, front, right side perspective view showing the unclaimed lid portion in an open position.
